UNITED STATES PATENT OFFICE

STACY B. HASELTINE, OF CHICAGO, ILLINOIS, ASSIGNOR TO W. H. MINER, INC., OF CHICAGO, ILLINOIS, A CORPORATION OF DELAWARE

CAR CONSTRUCTION

Application filed December 19, 1929. Serial No. 415,171.

This invention relates to improvements in car construction.

One object of the invention is to provide a combined locking and center pin structure for connecting the body and truck bolsters of railway cars, which is of rugged design and may be readily applied to and removed from the bolsters and has exceptionally great tensile strength to oppose forcible separation 10 of the bolsters and also great resistance against shearing action, wherein the combined locking and center pin structure comprises a pair of pin members which are separately and successively applied to the bolsters 15 to facilitate the assembling operation and are adapted to interlock to form a complete pin element, one of the pin members also interlocking with one of the bolsters to prevent relative rotation of the complete pin 20 structure with respect to said bolster and accidental disengagement of the complete pin.

Another object of the invention is to provide a two part combined locking and center pin for connecting the body and truck bolsters 25 of a railway car, wherein one of the pin members has shouldered engagement with both bolsters to prevent relative separation thereof and the other member also prevents separation of the bolsters when the same are 30 rotated relatively to each other by shouldered engagement respectively with one of the bolsters and the first named member.

A still further object of the invention is to provide a two part center pin of the character indicated in the preceding paragraph, 35 wherein the member having shouldered engagement with both bolsters has the shape of the means at one end thereof which has shouldered engagement with one of the bolsters 40 and the cross section of the opening of the corresponding bolster such that said end may be inserted therethrough while in one position, but is prevented from passing therethrough when given a partial turn to register with the shoulder adjacent said opening, and wherein the other member locks the 45 same in the last named position against rotation with respect to the corresponding bolster.

50 Other objects of the invention will more

clearly appear from the description and claims hereinafter following.

In the drawing, forming a part of this specification, Figure 1 is a top plan view of a portion of a body bolster of a railway car 55 illustrating my improvements in connection therewith. Figure 2 is a vertical, sectional view through the body and truck bolsters of a railway car, corresponding substantially to the line 2-2 of Figure 1. Figure 3 is a 60 vertical, sectional view taken in a plane at substantially right angles to the sectional view shown in Figure 2. Figures 4 and 5 are horizontal, sectional views corresponding respectively to the line 4-4 and the line 5-5 65 of Figure 2.

In said drawings, 10 designates the body bolster and 11 the truck bolster of a railway car. The body bolster is provided with the usual depending bearing projection 12 cooperating with a bearing block 13 mounted within a seat 14 at the top of the truck bolster. The bearing projection 12 and the block 13 are provided with the usual cooperating bearing surfaces of substantially spherical 70 form. The bearing block is provided with the usual upstanding annular flange 15 which engages within the pocket 16 provided in the bearing projection of the body bolster.

In carrying out my invention, I provide the body bolster, the truck bolster and the bearing block 13 with aligned center pin receiving openings 17, 18 and 19 respectively. The openings 17, 18 and 19 are preferably of 80 the same size and of similar cross sectional outline. As most clearly illustrated in Figures 4 and 5, each opening is of elongated cross sectional form, the narrower part of the opening being designated by 20 and the wider part by 21. The part 20 of each pin receiving opening has opposed walls 22 of cylindrical form which are concentric. The part 21 of each center pin receiving opening also has opposed substantially cylindrical walls 23-23 which are concentric with the walls 22-22 but offset outwardly with respect to the same. As will be evident, the offset walls 23-23 of the pin receiving openings in effect form vertical slots at opposite sides 90 of the pin receiving openings, which form 95 100

guides to accommodate certain parts of the center pin members while being applied to the bolsters, as hereinafter more fully pointed out.

The body bolster is provided with a pocket 24 located above the opening 17, the pocket being of greater width than the diameter of the part 20 of the opening and preferably corresponding in diameter to the diameter of the part 21 of said opening. As will be clear, a pair of shoulders 25—25 are thus provided at opposite sides of the narrower part 20 of the opening 17.

The truck bolster is also provided with a pocket 26 beneath the pin receiving opening 18 thereof. The pocket 26 is in the form of a channel, defined by the vertical spaced webs 27—27 of the truck bolster. The width of the pocket 26 is at least as great as the diameter of the larger part 21 of the opening 18 and as shown corresponds in width to said diameter. Opposed shoulders 28—28 are thus provided at opposite sides of the narrower part 20 of the opening 18.

My improved center pin proper comprises a connecting member A and a locking member B.

The member A has a shank 29 which extends through the center pin receiving openings of both bolsters. The shank 29 is of substantially cylindrical outline in cross section and of such a diameter that it will fit within the narrower part 20 of the pin receiving openings of the bolsters. At the lower end, the shank 29 is provided with a pair of laterally projecting arcuate flanges 30—30 at diametrically opposite sides thereof, which are adapted to cooperate with the shoulders 28 of the truck bolster. The flanges 30—30 are preferably of such a size that they will pass freely through the enlarged portions 21 of the pin receiving openings and will overlap the shoulders 28 when the member A is turned about its axis to an extent to register the flanges 30 with the shoulders 28—28. The flanges 30 are preferably of such a length that they will completely overlie the shoulders. Immediately adjacent the head portion at the bottom end of the member A, the shank 29 of the same is cut away on opposite sides to provide vertically disposed grooves 31—31, as clearly shown in Figure 5. At the upper end the shank 29 is bifurcated, as indicated at 32—32, thereby providing in effect a pair of vertically disposed parallel arms. At the outer end of each arm 32, the member A has a laterally projecting arcuate flange section 33, which corresponds in shape and size to the flange 30 at the opposite end of the member A and is preferably vertically aligned therewith. As will be evident, the flanges 33—33 together form a head member at the upper end of the member A having shouldered engagement with the shoulders 25—25 of the body bolster. The mem-

ber A may be assembled with the body and truck bolsters either by entering the same through the body bolster and passing the flanges 30—30 at the bottom end thereof through the laterally elongated portions of the pin receiving openings or by entering the same upwardly through the truck bolster and passing the flanges 33—33 at the upper end thereof through the laterally elongated portions of said pin receiving openings.

The member B has a shank 34 which extends through the pin receiving openings of the bolsters. At the upper end the shank 34 of the member B is provided with a substantially circular head 35 which bears on top of the flanges 33—33 of the member A.

The head 35 is preferably of the same diameter as the head formed by the flanges 33—33 of the member A and is provided with an upwardly extending eye member 36 to facilitate handling of the member B in applying and removing the same. Adjacent the head 35, the shank 34 of the member B is of substantially the same diameter as the head 35 and the head formed by the flanges 33 of the member A, fitting the larger part 21 of the pin receiving opening 17. The shank 34 is cut away at opposite sides, as indicated at 37—37, thereby providing vertically disposed grooves or slots adapted to accommodate the arms 32—32. At the lower end, the shank 34 is bifurcated, similarly to the upper end of the shank of the member A, thereby providing a pair of spaced arms 38—38 which embrace the corresponding end of the shank of the member A and engage within the grooves or slots 31—31 at opposite sides of said shank portion. At the bottom ends, the arms 38—38 of the member B are provided with laterally projecting arcuate flanges 39—39 which fit between the flanges 30—30 at the bottom end of the member A and form a complete annular head therewith. The flanges 39—39 are of such a size that they will pass freely through the enlarged portions 21 of the pin receiving openings in assembling the member B with the body and truck bolsters. The major portion of the shank 34 of the member B corresponds in diameter to the narrower parts 20 of the pin receiving openings, as clearly shown in Figures 2 and 3, the upper end portion of the shank 34 immediately adjacent the head 35 only being enlarged as hereinbefore pointed out.

In applying my improved center pin to the body and truck bolsters of a railway car for connecting the same, the member A is first applied either by insertion through the truck or body bolster. Assuming that the member A is applied by inserting the same upwardly through the truck bolster, the lugs or flanges 33—33 at the upper end of the same are registered with the larger parts 21 of the pin receiving openings and passed therethrough. After the member A has been completely in-

serted, the same is given a turn about its axis so as to aline the flanges 33—33 with the shoulders 25—25 of the body bolster. At the same time, the flanges 30—30 at the bottom end 5 of the member A will also be registered with the shoulders 28—28 of the truck bolster. As will be evident, the heads formed by the flanges at opposite ends of the member A will thus prevent separation of the body and truck 10 bolsters. Instead of inserting the member A upwardly through the truck bolster, the same may be applied by passing the same downwardly through the body bolster, as hereinbefore pointed out. In this operation, the 15 flanges 30—30 of the bottom head of the member A are first brought into the alinement with the larger portions 21 of the pin receiving openings and passed downwardly through said openings. When the member A has been 20 completely inserted, the same is turned in the manner hereinbefore pointed out to register the flanges at opposite ends thereof with the shoulders of the body and truck bolsters respectively.

25 After the member A has been applied, the locking member B is inserted through the top of the pocket 24 of the body bolster, the arms 38 being entered into the pin receiving openings at opposite sides of the shank of 30 the member A, the flanges 39—39 passing through the laterally enlarged portions 21 of the pin receiving opening. When the member B has been completely applied, the forked portion thereof embraces the shank 29 of the 35 member A at the lower end of the latter and the forked portion of the member A embraces the upper portion of the shank 34 of the member B, thereby interlocking the members A and B so that they are held against relative 40 rotation with respect to each other. Inasmuch as the upper end portion of the shank of the member B fits the larger portion 21 of the pin receiving opening 17, the member B is held against rotation with respect to the 45 body bolster. As the members A and B are interlocked, the entire pin is also held against rotation with respect to the body bolster.

When the body and truck bolsters of the 50 car are in transverse alinement, as for example when the car is running on straight track, the member A has shouldered engagement with both bolsters, thereby preventing separation of the same, the flanges 39—39 at the bottom end of the member B at this time 55 being out of alinement with the shoulders 28 of truck bolster. When the car is operated on curved track, the body and truck bolsters will be turned angularly relative to each other and inasmuch as the complete pin is locked against 60 rotation with respect to the body bolster, the truck bolster will turn with respect to the pin and the flanges 39—39 of the member B. These flanges will thus be brought into overlapping relation with respect to the shoulders 65 28—28 of the truck bolster, thereby assist-

ing in locking the bolsters together. In this connection, it is pointed out that any tendency of the bolsters to separate in a vertical direction will cause a lifting of the head formed by the flanges 33 of the member A, thereby also 70 lifting the head 35 of the member B and bringing the flanges 39—39 at the lower end of the member B into engagement with the shoulders 28 of the truck bolster.

In separating the body and truck bolsters, 75 the member B is first removed by lifting the same upwardly through the body bolster, thus withdrawing the same from engagement with the member A. After the member B has been removed, the member A may be freely rotated 80 to register the flanges thereof with the portions 21 of the pin receiving openings. The member A may then be withdrawn either by lifting the same upwardly through the body bolster or dropping the same through the 85 truck bolster.

From the preceding description taken in connection with the drawings, it will be evident that I have provided an exceedingly efficient and rugged center pin member of the 90 two part type, wherein additional strength is provided by a continuous head member, which is formed partly on each section of the pin. Further, maximum tensile strength opposing separation of the body and truck bolsters 95 is had by providing means on both members of the pin for locking the same to the bolsters.

I have herein shown and described what I now consider the preferred manner of carrying out my invention, but the same is merely illustrative and I contemplate all changes and modifications that come within the scope 100 of the claims appended hereto.

I claim:

1. In car construction, the combination 105 with body and truck bolsters having alined center pin receiving openings, and each bolster having a shoulder adjacent its opening; of a connecting member having enlargements at opposite ends and having a shank portion 110 extending through the openings of the bolsters, the enlargements of said member cooperating respectively with the shoulders of the body and truck bolster; and a locking member having a shank portion extending 115 through the openings of the bolsters and an enlargement at one end forming with the enlargement at the corresponding end of the first named member a complete annular head member cooperating with the shoulder of the 120 corresponding bolster, said locking member and connecting member having shouldered engagement with each other to transmit the force from said locking member through the connecting member to the shoulders of the 125 other bolster.

2. In car construction, the combination 130 with body and truck bolsters having alined center pin receiving openings; of a center pin member extending through said openings

and having shouldered engagement at opposite ends with said bolsters respectively to prevent separation thereof; and a locking member also extending through the openings of said bolsters, said locking member having means thereon for locking said first named member against rotation with respect to one of said bolsters while permitting relative rotation of the pin and other bolster, said locking member having shouldered engagement with said first named member and with said last named bolster when the latter is turned with respect to the other bolster.

3. In car construction, the combination with body and truck bolsters having alined center pin receiving openings, and each bolster having a shoulder at the outer end of its opening; of a connecting center pin member having head elements at opposite ends adapted to engage the shoulders of said bolsters respectively, the shape of one of said head elements and the cross section of said openings being such that said head element may be inserted therethrough while in one position but is prevented from passing therethrough when given a partial turn; and a second connecting center pin member having a shank portion extending through the pin receiving opening and having a head at one end bearing on the corresponding end of the first named member, and having a head element at the other end forming with the head element at the corresponding end of the other member a complete head member.

4. In car construction, the combination with body and truck bolsters having alined center pin receiving openings, each bolster having a shoulder at the outer end of its opening; of a two part center pin member connecting said bolsters, said pin having a two part head at one end, the parts of said head being respectively integral with said two members, said two part head cooperating with the shoulder of the corresponding bolster, one of said members having a head at the other end abutting the corresponding end of the other member and said last named member having a head at said last named end having shouldered engagement with the shoulder of the corresponding bolster, the shape of said last named head and the cross section of said openings being such that said head may be inserted therethrough while in one position but is prevented from passing therethrough when given a partial turn.

5. In car construction, the combination with body and truck bolsters having alined center pin receiving openings, each bolster having a shoulder at the outer end of its opening; of a two part center pin member connecting said bolsters, said pin having a two part head at one end, the parts of said head being respectively integral with said two members, said two part head cooperating

with the shoulder of the corresponding bolster, one of said members having a head at the other end abutting the corresponding end of the other member and said last named member having a head at said last named end having shouldered engagement with the shoulder of the corresponding bolster, the shape of said last named head and the cross section of said openings being such that said head may be inserted therethrough while in one position but is prevented from passing therethrough when given a partial turn, said members being interlocked against rotation with respect to each other and locked against relative rotation with respect to one of said bolsters, when completely assembled with the bolsters.

6. In car construction, the combination with body and truck bolsters having alined center pin receiving openings, each bolster having a shoulder adjacent its opening; of a two part center pin, each part having a shank extending through the center pin receiving openings, said pin having a two part head at one end cooperating with the shoulder of one of said bolsters, the parts of said head being formed integral with said shanks respectively, the shape of each of the head parts and the cross section of said openings being such that each of said head parts may be separately inserted therethrough while in one position, but is prevented from passing therethrough when given a partial turn, said pin having means cooperating with the shoulder of the other bolster, including a head member on the shank of one of said pin parts and means on the shank of the other pin part having shouldered engagement with said head member, said last named pin part being interlocked with the last named bolster to prevent relative rotation, and said pin parts being interlocked against rotation with respect to each other.

7. In car construction, the combination with body and truck bolsters having alined center pin openings, each bolster having a shoulder adjacent its opening said opening being elongated in cross section; of a center pin comprising a connecting member and a locking member, both of said members having shank portions extending through the bolsters, said shank portions being interlocked against relative rotation, said connecting member having a head at one end thereof having engagement with the shoulder of one of said bolsters, and said locking member having a head portion at the corresponding end bearing on said head of the connecting member, said pin having a two part head at the other end cooperating with the shoulder of the other bolster, one part of said head being formed on the connecting member and the other part on the locking member, each of said parts corresponding in cross sectional outline to the cross sectional out-

line of the pin receiving openings, whereby each of said head parts will pass freely through said pin receiving openings when the cross sectional outline of the head part is alined with the cross sectional outline of said openings, said connecting member being displaceable with respect to the shoulders of the bolsters to interlock the same therewith, the shank of said locking member having shouldered engagement with one of said bolsters to prevent rotation thereof with respect to the bolster, thereby also holding the pin against rotation with respect to said bolster.

8. In car construction, the combination with body and truck bolsters having alined center pin receiving openings and each bolster having a shoulder adjacent the outer end of its opening; of a two part center pin having head members at opposite ends thereof cooperating with the shoulders of the bolsters respectively, each of the parts of the pin having a shank extending through the pin receiving openings, each shank having a portion thereof bifurcated and embracing the remainder of the other shank.

25 In witness that I claim the foregoing I have hereunto subscribed my name this 17th day of December, 1929.

STACY B. HASELTINE.
